Primary Examiner — Phillip S Hyder*Assistant Examiner* — Darlington Ly(74) *Attorney, Agent, or Firm* — Crowell & Moring LLP(57) **CLAIM**

The ornamental design for a front fascia of a vehicle, toy, and/or replicas thereof, as shown and described.

DESCRIPTION

FIG. 1 is a top, front, and left-side perspective view of a front fascia of a vehicle, toy, and/or replicas thereof according to our design;

FIG. 2 is a left side view thereof, the right side view being mirror symmetrical; and,

FIG. 3 is a front view thereof.

The broken lines shown in the drawings illustrate portions of the front fascia of a vehicle, toy, and/or replicas thereof that form no part of the claimed design. Also enclosed is a set of photographs of an embodiment of the design.
